W. P. Troubridge
by his attorney
John W. Folger

United States Patent Office.

WILLIAM P. TROWBRIDGE, OF NEWTOWN, NEW YORK.

Letters Patent No. 94,529, dated September 7, 1869.

IMPROVED BRIDGE.

The Schedule referred to in these Letters Patent and making part of the same.

To whom it may concern:

Be it known that I, WILLIAM P. TROWBRIDGE, of Newtown, Queens, county, New York State, have invented certain new and useful Improvements in the Construction of Bridges; and I hereby declare the following to be a full, clear, and exact description of the same, reference being had to the accompanying drawings, in which—

Figure 1 is a perspective view of a completed truss-bridge, made in accordance with my invention.

Figure 2 is a side elevation of the same, representing the half trusses as not yet joined.

My invention is especially applicable to cases when the great length of span, the necessity of a great altitude for the bridge, and the difficulties of erecting auxiliary staging for erecting the structure, render the use of ordinary single trusses difficult, if not impracticable, but this system may be used to advantage in any case.

The plan which I propose may be described as follows:

Two separate and independent girder-beams or trusses, A B, are constructed on the land, at the terminus of the bridge-crossing, one upon each bank, and in the line of the bridge, as seen in fig. 2.

The trusses or girders are built of such strength and form, that they may be pushed or launched out over the channel, the projecting ends of each truss spanning one-half the channel, and meeting over the middle of the channel, as represented in fig. 1.

During the operation of pushing out, the shore-ends are loaded with temporary weights to counterbalance the projecting parts.

After the projecting ends are brought together, they are permanently united in such a manner that the two half spans will become one single or continuous truss, girder, or beam.

The shore-ends may then be fastened with bolts or tie-rods to the piers, and the auxiliary counterweights removed.

The masses of the piers or masonry will thus be made to act as the counterweights.

In order to provide for the sliding of the bridge on the abutments by contraction and expansion, rollers *a*, after the bridge is in place, may be placed under the trusses, and between the trusses and piers or bed on which the trusses rest, and the rods or bolts which tie the trusses to the piers would also have a sufficient adjustability to allow of this slight motion.

As regards the form of the half trusses or girders, they may be made as indicated in the drawings, or in the form of simple trusses or tubes, or their construction may be otherwise varied in the manner well known to those skilled in the art to which this invention pertains.

The trusses can be readily built and completed on a level with the ground, and then raised up and placed upon the piers or masonry *D*, from which they are to be projected.

It will be seen that several important points are gained by this construction:

First, each separate half truss being made to bear the greatest load that will come upon it before the two are joined, after they are joined the two will bear a greatly increased weight without deflection, by virtue of the single beam which they form, and consequently it is possible to build, for a given load and span, the whole truss of lighter proportions.

Second, as the overhanging half girders extend back inland, and the inner ends are fixed to the piers, increased strength is thereby added to the entire structure.

Third, contraction and expansion by heat and cold will not, as in a simple suspension-bridge, cause the middle of the span to droop.

Fourth, it is possible to attain greater spans by this method than by any other, except the simple suspension-bridge, and, at the same time, retain the virtue of the beam or girder-system; as to stiffness, freedom from vibrations, and oscillations.

Fifth, no auxiliary staging is required for the construction.

Sixth, the half trusses may be constructed on a lower level, and then raised up before being launched out.

Having now described my invention, and the manner in which the same is or may be carried into effect,

What I claim, and desire to secure by Letters Patent, is—

The construction of bridges, substantially in the manner and for the purposes herein shown and specified.

In testimony whereof, I have signed my name to this specification, before two subscribing witnesses.

W. P. TROWBRIDGE.
